PHONOGRAPH ON-OFF CONTROL

Filed Oct. 8, 1947

UNITED STATES PATENT OFFICE

2,567,318

PHONOGRAPH ON-OFF CONTROL

Gustav F. Braun, Elizabeth, N. J., assignor to
 Thomas A. Edison, Incorporated, West Orange,
 N. J., a corporation of New Jersey

Application October 8, 1947, Serial No. 778,537

1 Claim. (Cl. 274—1)

1
 This invention relates especially to phonographic machines adapted for the reproduction of recorded dictation.

More especially, the invention relates to dictating machines which have a first receiver permanently mounted on a removable section of the cabinet, a handpiece including a start-stop control and/or a second receiver, circuit means for connecting said receivers selectively to the outlet of the machine and setting the acoustic output from the receivers at predetermined relative levels, a support on the removable cabinet section for the handpiece which is coupled to an on-off control for the machine to place the machine in inoperative condition when the handpiece is on the support, and separable connections to the first receiver and support to permit ready removal of the cabinet section.

The invention resides in novel and improved combinations and subcombinations of the aforementioned apparatus and will be apparent from the following description and the appended claim.

In the description of my invention reference is had to the accompanying drawings, of which:

Figure 1 is a perspective view of a dictating machine adapted for the selective recordation and reproduction of dictation and incorporating my invention;

Figure 2 is a fractional sectional view taken substantially on the line 2—2 of Figure 1;

Figure 3 is a fractional sectional view showing parts of the apparatus of Figure 2 as seen from the back side of that figure;

Figure 4 is a fractional section taken substantially on the line 4—4 of Figure 3; and

Figure 5 is a diagrammatic view of circuits and mechanism according to my invention.

The dictating machine illustrative of my invention and shown in the accompanying drawings comprises a frame 10 having a top plate 11 provided with depending side legs 12 (Figure 2). At the front the frame has a transverse member 13 the upper section 13a of which is vertical and the lower section 13b of which inclines downwardly and forwardly. This frame member 13 has a window 14 in its vertical section 13a. Below this window on the lower section 13b there is mounted a guide 15 adapted to receive an index slip (not shown) such as is well known in the art.

The cabinet comprises a base section 16 on which rests the frame above described, and a removable upper section 17 which is normally held permanently in place by screws 18 which extend through the side walls of the upper section into the side legs of the frame (Figure 1).

2
 In its mounted position, the upper cabinet section may rest on the base section 16, as at 19, and the joint between the sections may be covered by a bead 20 (Figure 2). The top cabinet section 17 has a front wall the upper portion 21a of which is vertical and the lower portion 21b of which is inclined downwardly and forwardly. These cabinet wall portions are substantially in the planes of the frame sections 13a and 13b respectively, and have a window 22 leaving exposed the transverse frame member 13. In the upper righthand portion of the top cabinet section 17 there is a recess 23 to provide access for the mounting and removal of a disk record on and from the machine as in the manner explained in the Somers application Serial No. 773,129, filed September 10, 1947, now Patent No. 2,538,392, issued January 16, 1951, and having a common assignee with the present application.

20 The operating mechanism of the machine need not be described for the purposes of the present invention, but if desired reference may be had to the abovementioned Somers application for a description of the main components thereof. Sufficient it to say for the present application that this mechanism comprises a phonographic recorder and reproducer adapted for selective engagement with the record, a carriage for the recorder and reproducer, audio circuits including an amplifier 24, diagrammatically shown in Figure 5, and a drive mechanism including a motor 25, diagrammatically shown in Figure 5, for turning the record and concomitantly feeding the carriage thereacross. The recorder and reproducer may 25 be placed selectively into and out of contact with the record by manipulating a control lever 26 downwardly and upwardly from its neutral position shown in Figure 1, and the carriage may be manually moved across the record by this same control lever as whenever the latter is in its neutral position. This control lever projects through a slot 27 in a closure 28 for the window 14. This slot extends lengthwise of the closure so that the closure does not obstruct the lateral movement of the control lever attendant with the traveling movement of the carriage; however, the closure partakes of the upward and downward turning movement of the control lever into reproducing and recording positions. Moved with the carriage is an arm 29 overhanging the guide 15, which carries two key-type punches 30 and 31 for making apertures in the index slip to indicate lengths of separate items of dictation, places of errors and corrections, etc.

50 55 As is typical, the present machine is provided

with a handpiece 32 which has an electroacoustical transducer 33 mounted in a circular end portion thereof, and a manually operable control lever 34 mounted in a handle portion thereof, the control being provided as a means for starting and stopping the record rotation and carriage movement. This transducer, or speaker, and manual control are connected electrically to the machine by a cable 32a. In accordance with certain aspects of my invention, the handpiece may have either the transducer 33 or control 34 but not necessarily both; accordingly, in the appended claim the term "handpiece" is to be construed as including the transducer and/or the control. The transducer 33 is preferably a small type of loudspeaker adapted to serve also as a microphone whenever the machine is used for recording dictation; however, since for the purposes of the present invention its prime function is that of a receiver, it is hereinafter so referred to. The manner in which the control 34 starts and stops the machine need not be herein described since it may be of any of the different forms well known in the art and is not important to the invention.

In addition to the receiver 33, there is a second receiver or speaker 35 which is provided as a permanent part of the machine. In order that this speaker may utilize the upper cabinet section as a baffle, to enable good reproduction of the lower frequencies in the audio spectrum, it is mounted on the cabinet section 17 with the edge of the cone thereof sealed in relation to the wall of the cabinet. Also the speaker is resiliently mounted so that the reproduced sound vibrations are not readily transmitted to the cabinet. For example, ahead of the speaker there is a window in the front vertical wall 21a covered by an open grille 36. This grille is held in place by three screws 37 which pass through the cabinet wall and thread into a backing plate 38 having a central opening corresponding to the window just mentioned. Surrounding this central opening is a ring 39 of relatively thick sponge rubber which has one face thereof secured permanently to the plate 38 by a suitable adhesive of a type which has good adherence to both rubber and metal. To the other face of this rubber ring there is secured the rim of the cone of the speaker 35 also by a suitable such adhesive. Thus the speaker is resiliently supported and sealed to the cabinet.

Although the cabinet section 17 is normally a permanently-mounted one, it is removed as whenever the machine is serviced, etc. In order to permit easy removal of this cabinet section 17, the electrical circuit to the speaker 35 has a separable plug and socket connector 40. The plug of this connector comprises two pins 41 mounted on an insulating plate 42 which is in turn mounted on a bracket 43 having a base formed by the backing plate 38 aforementioned. These pins are connected by leads 44 to the speaker 35. The socket of this connector 40 comprises an insulating block 45 provided with a flanged base 46 which is held by screws 46a to the top plate of the frame 10. The block has two pin-receiving apertures 47 into which project respective spring contact fingers 48. These contact fingers have connector lugs projecting from the block into which are connected the leads 49.

In Figure 5 the amplifier 24 is shown as having a pair of audio output terminals 50. One of the leads 49 connects to one of these terminals, and the other of these leads connects to a termi-

nal 51 of a single-pole double-throw selector switch 52 having a pole 53 and a second terminal 54. This switch is mounted on the side of the cabinet at the junction between the upper and lower cabinet sections 16 and 17, and is provided with a knob 55 for throwing the pole from one position to the next (Figure 1). This pole is connected by a lead 56 to the other outlet terminal 50. Thus in the position of the switch 52 shown in Figure 5, the speaker 35 is connected to the output of the amplifier.

A lead 57 running from the lead 49 and comprised in the cable 32a connects to one terminal of the receiver 33. The other terminal of this receiver is connected by a lead 58, also comprised in the cable 32a, to the pole 53 of the switch 52. Thus when the selector switch is thrown from the position it occupies in Figure 5 the amplifier output is connected to the hand receiver.

In series with the receiver 33 is an attenuator unit 59 which may be simply a resistor. This resistor is provided as a means for setting the acoustic output level of the receiver 33 to a predetermined value in relation to that of the speaker 35. Preferably this attenuator unit is adjustable as indicated in Figure 5.

On the cabinet section 17 there is a support 60 for the handpiece 32. This support comprises a bail 61 which straddles the speaker 35 and has a forwardly-extending fork 62 to receive the neck of the handle portion of the handpiece. The two legs of the bail extend through clearance openings 63 in the cabinet section 17 and are pivoted at 64 within the cabinet to apertured ears 65 turned over from the plate 38 (Figures 2 and 3). Connected from a cross pin 66 on a depending arm 67 of the bail and a bracket 68 on the cabinet is a tension spring 69 which urges the bail upwardly into the position defined by the abutment of the arm 67 against the front vertical wall 21a of the cabinet. When the handpiece is placed on the support 60, the latter is moved downwardly against the action of the spring 69 by the weight of the handpiece into a position defined by the abutment of an upright arm 70 on the bail against the front wall 21a of the cabinet (Figure 2). This downward movement causes the machine to be turned off as is herein next explained.

In the cabinet at the left side of the speaker 35 there is a bracket 71 having one arm 71a secured by a screw 72 to an upstanding standard 73 of the frame 10 and having a turned-over lug 74 held by a screw 75 to the front end of the standard. This bracket 71 has an upright U-shaped member 71a embracing a stack 76 of insulating plates. Interposed between the plates of this stack are two contact springs 77 and 77a of a switch 78. These contact springs are placed side by side and have switch contacts at their lower ends as shown in Figure 4. Insulated by the stack 76 at the rear of the contact springs 77 and 77a is a single contact member 79 of resilient material having two contacts urged normally against the respective contacts of the springs 77 and 77a. Between the contact springs 77 and 77a there is a plunger 80 which passes through apertures provided in the U-member 71a and through a central aperture in the contact member 79. This plunger is urged forwardly by the abutment of the contact member 79 against a depending lug 81 of the plunger. This lug 81 is positioned within the U-member 71a and serves by its abutment against the front

leg of this member to retain the plunger in place.

The front end of the plunger 80 has a vertical face 82 which lies just back of the cross pin 66 carried by the support 60. When the handpiece is placed on the support, the pin is moved rearwardly against the plunger to open the circuit between the contact springs 17 and 17a. These contact springs are connected by a pair of leads 83 in a circuit of the motor 25 leading to a power-supply cable 84 for the machine (Figure 5). 10 Thus, when the handpiece is put on the support 60—which is its normal resting position whenever the machine is not in use—the motor is at standstill to place the machine out of operation. Preferably the amplifier is left in a heated condition while the motor is shut off since it requires a few moments to heat up to operating condition and it is desirable that the machine be ready for immediate use. Therefore the amplifier is connected to the power-supply cable 84 by separate leads 85 as through an amplifier on-off switch 86.

It will be noted that the coupling of the support 60 to the plunger 80 is by mere abutment of one against the other and is therefore a separable one which permits the cabinet 17 to be removed at any time without being first uncoupled from any parts which form the operative connections of the machine. Also the cabinet section may be remounted at will and when so remounted the coupling of the support to the on-off switch is automatically effected. To facilitate the positioning of the cross pin 66 ahead of the plunger as the cabinet section 17 is mounted, the upper portion of the plunger is beveled at 87.

The embodiment of my invention hereinabove described is intended to be illustrative and not limitative since the same is subject to changes and modifications without departure from the 40

scope of my invention, which I endeavor to express according to the following claim.

I claim:

In a phonographic machine comprising a frame, a cabinet enclosing said frame and having a removable section and a handpiece for said machine; the combination of an on-off control for said machine mounted on said frame, said control being biased into "on" position, a horizontally-movable plunger for operating said control to "off" position, said plunger being carried with said control and being urged outwardly with respect thereto, a support for said handpiece pivoted to said removable cabinet section and projecting therefrom, means biasing said support upwardly into a raised position but with a force less than the weight of said handpiece on the support, and an arm on said support having means thereon which when said removable section is in mounted position is held normally free of said plunger by said biasing means in a position for abutment against the end of said plunger, to move the plunger inwardly and cause said control to be moved to "off" position, as said handpiece is placed on said support.

GUSTAV F. BRAUN.
